DESIGN FOR A BEVERAGE BOTTLE CASE

Albert J. Gerber, University City, Mo., assignor to Gerber Plastic Company, St. Louis, Mo., a corporation of Missouri

Application April 22, 1946, Serial No. 128,826

Term of patent 7 years

(Cl. D58—13)

To all whom it may concern:

Be it known that I, Albert J. Gerber, a citizen of the United States, residing at University City, county of St. Louis, State of Missouri, have invented a new, original, and ornamental Design for a Beverage Bottle Case, of which the following is a specification, reference being made to the accompanying drawing, forming a part thereof, in which Figure 1 is a perspective view of a beverage bottle case embodying my new design, Figure 2 is a top plan view thereof, Figure 3 is a side elevational view thereof, Figure 4 is a bottom plan view thereof, Figure 5 is an end elevational view thereof, and Figure 6 is a fragmentary sectional view illustrating the appearance of the handle and bottom wall.

I claim:

The ornamental design for a beverage bottle case, substantially as shown.

ALBERT J. GERBER.
